UNITED STATES PATENT OFFICE.

FREDERICK WILLSON, OF MOUNT PENN, PENNSYLVANIA, ASSIGNOR TO WILLSON PRODUCTS, INC., OF READING, PENNSYLVANIA, A CORPORATION OF PENNSYLVANIA.

DESIGN FOR GOGGLES.

Application filed February 27, 1929. Serial No. 30,246. Term of patent 14 years.

To all whom it may concern:

Be it known that I, FREDERICK WILLSON, a citizen of the United States, residing at Mount Penn, in the county of Berks and State of Pennsylvania, have invented a new, original, and ornamental Design for Goggles, of which the following is a specification, reference being had to the accompanying drawings, forming part thereof.

In the drawings:

Fig. 1 is a front view of goggles embodying my new design.

Fig. 2 is a corresponding top view.

Fig. 3 is a corresponding bottom view.

Fig. 4 is an end view.

I claim:

The ornamental design for goggles, as shown.

In testimony whereof I affix my signature.

FREDERICK WILLSON.
